UNITED STATES PATENT OFFICE.

ALBEN E. LUNDELL, OF NEW YORK, AND GEORGE THOMPSON, OF MOUNT VERNON, NEW YORK, ASSIGNEES TO WESTERN ELECTRIC COMPANY, INCORPORATED, OF NEW YORK, N. Y., A CORPORATION OF NEW YORK.

AUTOMATIC TELEPHONE SYSTEM.

1,332,222.

Specification of Letters Patent.

Patented Mar. 2, 1920.

Application filed April 13, 1918. Serial No. 228,344.

To all whom it may concern:

Be it known that we, ALBEN E. LUNDELL and GEORGE THOMPSON, citizens of the United States, residing at New York, in the county of Bronx, State of New York, and at Mount Vernon, in the county of Westchester, State of New York, respectively, have invented certain new and useful Improvements in Automatic Telephone Systems, of which the following is a full, clear, concise, and exact description.

This invention relates to telephone exchange systems and more particularly to telephone exchange systems in which connections are established by means of automatic switches under the control of a calling subscriber.

It is the object of this invention to provide an exchange system of large capacity which will utilize a minimum of apparatus and which will operate rapidly and efficiently.

It is more specifically the object of this invention to provide an improved coin collect and metering system to be used in connection with an automatic telephone system.

A feature of the invention is the utilization of common coin collect and metering apparatus which may be operated to release the calling subscriber's line so that it may be seized as a called line and so that he may initiate a second call in as short a time as possible after he has taken steps to release the apparatus.

An additional feature is the use of quick-acting switches to associate controlling apparatus common to a large number of subscribers with apparatus which a calling subscriber has taken for use.

It is thought that the invention will be best understood from the following detailed description, reference being had to the accompanying drawings.

In the drawings, Figures 1 to 7 inclusive, illustrate diagrammatically the circuits and necessary portions of the apparatus of a telephone system required to embody the features of the present invention.

Fig. 1 shows a calling subscriber's line, together with a distributing switch individual to such line, and the circuits of a selector switch; Fig. 2 shows two quick-acting

switches which may be used to associate common controlling apparatus with a selector switch taken for use. Within the dotted rectangle in Fig. 2 is shown metering and coin return apparatus, together with a controlling sequence switch therefor; Fig. 3 shows portions of a register controlling apparatus, together with a special coin return device. The coin return device is shown within the dotted rectangles in the upper left-hand portion of Fig. 3. The contacts shown within the dotted lines are controlled by the sequence switch diagrammatically indicated therein. Fig. 4 shows register controlling circuits; Fig. 5 shows a set of registers and certain of the contacts controlled by them; Fig. 6 shows the wiring of additional contacts controlled by the registers of Fig. 5; and Fig. 7 shows sending equipment including a set of counting relays, controlling relays and an associated sequence switch.

Associated with each subscriber's line is a distributor switch individual to such line. Each switch consists of a movable brush carrier which may be advanced over a contact bank in which the terminals are arranged in an arc of a circle, each switch having access to a number of common trunk lines, the number of such trunk lines being dependent upon traffic conditions. Since switches operated step by step by means of a ratchet and pawl device are old in the art, it has not been considered necessary to disclose the mechanical structure of the distributing switch. The switch wipers are advanced in response to the actuation of a stepping magnet 10 and are held in an advanced position by means of a retaining pawl which is controlled by the cutoff relay 11, the arrangement being such that as long as the cutoff relay 11 is energized, the retaining pawl will be effective; but as soon as the cutoff relay is deenergized, the switch will be released. As soon as the wipers leave their normal position, contacts 12 and 13 are closed, while contact 14 is opened. The arrangement of the bank is such that the wipers are normally in engagement with a set of contacts shown at 15, 16 and 17. Upon completion of the first step, the wipers will engage contacts 18, 19 and 20 which are

unwired, and upon the completion of the second step, the wipers will engage the terminal set multiplied to the first trunk line. The wipers will then be advanced by a hunting movement until an idle trunk is found.

The coin device 334 shown associated with the substation 21 may be of any desired character, the only requisite being that it is provided with a polarized operating magnet and has contacts arranged so that it is necessary to deposit a coin therein in order to complete the circuit of the line relay. The mechanism of a coin device suitable for operation in connection with the system of the present invention is shown in Patent 1,076,285, issued to W. F. Hosford, October 21, 1913. A suitable circuit arrangement for a device of this character is shown in Patent 1,243,314, issued October 16, 1917, to A. E. Lundell.

The operation of the system is as follows. When the subscriber at substation 21 inserts a coin in the coin device and then removes his receiver from the switchhook, a circuit will be completed from grounded battery, resistance 22, terminal 17, brush 23, right-hand and left-hand windings of line relay 24, inner lower armature and back contact of cutoff relay 11, through the loop of the calling subscriber's line, upper armature and back contact of relay 11 to ground. Relay 24 is energized and completes a circuit from grounded battery, winding of stepping magnet 10, inner armature and front contact of relay 24, outer lower armature and back contact of relay 11, to ground. In response to the actuation of magnet 10, the brushes 23, 25 and 26 are advanced one step onto the blank terminals 18, 19 and 20, and at the same time, the off-normal contacts 12 and 13 are closed, and the off-normal contact 14 is opened. The opening of contact 14 opens the circuit to cutoff relay 11 and prevents the calling line from being seized as a called line by any subscriber, it being understood that conductor 27 leads to the test multiples of the calling line at final connector switches. With the brushes 23, 25 and 26 positioned on a blank terminal set, relay 24 is deenergized, but since contact 12 is closed, a stepping circuit is now completed from grounded battery, winding of magnet 10, armature and back contact of magnet 10, off-normal contact 12, outer lower armature and back contact of relay 11, to ground. Stepping magnet 10 is energized and interrupts its own circuit to advance the distributing switch brushes over the trunk terminals until an idle trunk is found. The test terminals of idle trunks will be characterized by the presence of full battery potential thereon. Busy trunks will be characterized by a reduced potential. When a test brush 23 engages terminal 28 which, it will be assumed, is the test terminal of the first idle trunk, a circuit

is completed from grounded battery, winding of relay 29, lower contacts of sequence switch spring 30, terminal 28, brush 23, right-hand and left-hand windings of relay 24, inner lower armature of relay 11, the loop of the calling subscriber's line, upper armature and back contact of relay 11, to ground. Relays 29 and 24 are energized in this circuit and relay 24 at its inner armature completes a holding circuit for magnet 10 from grounded battery, winding of magnet 10, inner armature and front contact of relay 24, outer lower armature and back contact of relay 11, to ground. Magnet 10 can now no longer interrupt its own circuit and the brushes are brought to rest. At its outer armature, relay 24 completes a holding circuit for itself and relay 29 from grounded battery, winding of relay 29, lower contacts of sequence switch spring 30, terminal 28, brush 23, right-hand winding of relay 24, outer armature and front contact of relay 24, contact 13, right and left-hand windings of message register magnet 70, winding of cutoff relay 11, to ground. Cutoff relay 11 is energized, but magnet 70 being marginal is not operated at this time due to the resistance of relay 29 being in series with it. Cutoff relay 11 upon operation removes the control of line relay 24 from the calling subscriber and opens the circuit of stepping magnet 10, which releases without, however, advancing the switch, since this magnet is arranged to advance the brushes of the distributing switch upon its energization.

The energization of relay 29 completes a circuit from grounded battery, power magnet of sequence switch 32, upper left-hand contact of sequence switch spring 33, conductor 34, right-hand armature and front contact of relay 29, to ground, for moving this sequence switch out of position 1 and into position 2.

When sequence switch 32 arrives in position 2, circuits are completed to operate the quick-acting switch shown at the right in Fig. 2. This switch is utilized to associate sending apparatus common to the subscribers' lines with a connecting link taken for use. The preferred form of this switch is essentially similar in construction to the crossbar switch shown and described in Re-issue Patent No. 14,236, issued December 26, 1916, to J. N. Reynolds. Only such parts of the switch and circuits will be described as are necessary to understand the operation of this type of switch in the present system.

In the present adaptation of the cross-bar switch, there is provided for each set of sending equipment, a vertical bar 35 carrying a plurality of sets of multiple contact members such as 36, 37, 38, 39, 40 and 41. For each individual connecting link, there is provided a horizontal longitudinally movable cross-bar 42. Each horizontal bar is pro-

vided with a plurality of sets of multiple contact members 43, 44, 45, 46, 47 and 48, there being a set of these contact members in operative relation to contacts carried by each of the vertical bars. A setting magnet 49 is provided for each vertical bar and upon energization rotates the associated vertical bar to an extent such that upon longitudinal movement of a bar 42, the corresponding contact members will be engaged. A trip magnet 50 common to all the vertical bars will then be energized to allow the bar 35 to return to normal position where its contact members will be out of the path of any other horizontal bar which may subsequently be operated. The contacts 51, 52 and 53 are operated in accordance with whether or not the associated vertical bar is in its normal position.

When the operating lever 56 of a vertical trunk bar is operated, it is latched in back of a projection 67 in proper relation thereto, these projections 67 being carried on a pivoted bracket 68 which is controlled by the common trip magnet 50. When magnet 50 operates, it allows the set vertical bar to be returned to its normal position by the action of a spring member 69 on the latched bar 54. This action of this spring member 69 also allows the contact 57 to be closed until another bar is set for the purpose previously set forth.

The bar 54 is slidably mounted and is provided with notches 55 in proper relation to the operating levers 56 of the respective vertical bars. Common contact 57 is closed while any one of the vertical bars is being set in order to close the circuit of a cutoff relay 58 to prevent any horizontal bar from being actuated while a vertical bar is being set. Stepping magnet 59 is provided to advance wipers 60 and 61 over terminal sets 62 and 63, respectively, by means of a ratchet and pawl device 64. A test relay 65 determines which vertical bar is next to be taken for use. A magnet 66 is individual to each horizontal bar and is double wound, the arrangement being such that current through both windings is necessary to cause the magnet to operate, but after having been energized current through the right-hand winding alone will be sufficient to maintain its armatures in an actuated position.

The general operation of the switch is such that a vertical bar 35 will be in its set position and another trunk bar will be pre-selected, that is, the wipers 60 and 61 will be in engagement with contacts 62 and 63, respectively, associated with an idle vertical bar, so that when the set bar is released, due to the actuation of magnet 50, the magnet 49 associated with the preselected bar will be energized as soon as the latched bar 54 has been returned to its normal position.

When the magnet 49 of such preselected bar

has been actuated to set the preselected bar, contact 53 individual to such preselected bar will be closed, and a circuit will then be closed for the test relay 65 by way of wiper 60 and contact 62 to complete a self-interrupting circuit for magnet 59 which will advance the wipers 60 and 61 to preselect another idle bar. As long as the wiper 60 is passing over a contact 62 associated with a busy bar or a set bar, ground will be found on the terminal 62, either by way of contact 53 or by way of contact 52, over conductor 110 as will be presently seen. When an idle bar is found, test relay 65 is deenergized and the wipers 60 and 61 are brought to rest.

With sequence switch 32 in position 2, a circuit is completed from grounded battery, right-hand winding of operating magnet 66, conductor 71, upper right-hand contact of sequence switch spring 72, right-hand armature and front contact of relay 29, to ground. At the same time a circuit is completed from grounded battery, armature and back contact of relay 58, left-hand winding of magnet 66, armature and back contact of magnet 66, conductor 73, lower right-hand contact of sequence switch spring 72, right-hand armature and front contact of relay 29, to ground. A circuit being closed through both windings of magnet 66, this magnet is energized and attracts its armatures, opening the circuit through its left-hand winding so that subsequent operation of relay 58 will have no effect on this magnet since the circuit through its right-hand winding is sufficient to maintain it energized. The actuation of magnet 66 operates the horizontal bar 42 to move it to the right and cause the engagement of contacts 43, 44, 45, 46, 47, 48 with contacts 36, 37, 38, 39, 40, 41, respectively. A circuit is now completed from grounded battery, winding of relay 74 (Fig. 3), lower and upper right-hand contacts of sequence switch spring 75, right-hand contact of sequence switch spring 76, armature and back contact of relay 77, conductor 78, contacts 39 and 46, conductor 79, upper right-hand contact of sequence switch spring 30, left-hand armature and back contact of relay 31, terminal 28, brush 23, right-hand winding of relay 24, outer armature and front contact of relay 24, off-normal contact 13, windings of magnet 70, winding of cutoff relay 11, to ground. Relay 74 is energized and locks itself to the above traced ground through its left-hand armature and front contact.

The energization of relay 74 completes a circuit from grounded battery, winding of slow release relay 98, lower contacts of sequence switch spring 99, conductors 100, 101 and 102, right-hand armature and front contact of relay 74, to ground. Relay 98 is energized and completes a circuit from

- grounded battery, power magnet of sequence switch 103, lower right-hand contact of sequence switch spring 104, left-hand armature and front contact of relay 98, to ground, for moving this sequence switch out of position 1 and into position 2 under the control of its master contact 105. With sequence switch 103 in position 2, a circuit is completed from grounded battery, power magnet of sequence switch 106, upper right-hand contact of sequence switch spring 107, contacts of sequence switch spring 108, left-hand armature and front contact of relay 98, to ground, for moving this sequence switch out of position 1 and into position 2 under the control of its master contact 109.
- As soon as sequence switch 106 reaches position 1, a circuit is completed from grounded battery, winding of trip magnet 50, contact 51, conductor 110, upper right-hand contact of sequence switch spring 111, to ground. The energization of magnet 50 rotates the bracket 68 about its pivots to such an extent that the projection 67 will be drawn out of the path of the operating lever 56 and the common latch bar 54 will be moved to the right by the spring member 69. A circuit is then completed from grounded battery, winding of set magnet 49 of the vertical bar which had been pre-selected contact 63, individual to such bar, wiper 61, left-hand armature and back contact of relay 65, contact 57, to ground. At the same time a circuit is completed from grounded battery, winding of relay 58, contact 57, to ground. Relay 58 is energized to prevent any horizontal bar from being actuated until the preselected bar has been set. As soon as the preselected bar has been set, its contact 53 will be closed, whereupon a circuit will be completed from grounded battery, winding of test relay 65, wiper 60, contact 62, associated with the bar which has just been set, contact 53, to ground.
- Relay 65 upon energization completes a circuit from grounded battery, right-hand armature and front contact of relay 65, winding of stepping magnet 59, armature and front contact of such magnet, to ground.
- The wipers 60 and 61 are now advanced to preselect another bar. As soon as a bar is found which is not in use nor set, ground will no longer be found on the terminals 62, and relay 65 will be deenergized, causing the wipers 60 and 61 to come to rest to pre-select another trunk bar. It is thus seen that there is always one bar in set position ready for seizure by the next horizontal bar to be actuated and that another vertical bar is preselected in readiness to be set as soon as the set bar has been taken for use and released.

Simultaneously with the operation of horizontal bar 42 a circuit is completed for relay 80 (Fig. 4) from grounded battery,

winding of relay 80 (Fig. 4), conductor 81, right-hand armature and back contact of relay 82, conductor 83, contact of sequence switch spring 84, conductor 85, contacts 40 and 47, conductors 86 and 87, lower left-hand contact of sequence switch spring 88, terminal 89, brush 25, inner lower armature and front contact of cutoff relay 11, the loop of the calling subscriber's line, the upper armature and front contact of cutoff relay 11, brush 26, terminal 90, lower right-hand contact of sequence switch spring 91, conductors 92 and 93, contacts 48 and 41, conductor 94, upper contact of sequence switch spring 95, conductor 96, upper right-hand contact of sequence switch spring 97, to ground. When sequence switch 108 reaches position 2, the original energizing circuit of relay 98 is broken, but with relay 80 energized, relay 98 is maintained energized over a circuit from grounded battery, winding of relay 98, conductor 112, armature and front contact of relay 80, conductor 113, right-hand armature and front contact of relay 74, to ground. A circuit is now completed from grounded battery, power magnet of sequence switch 114 (Fig. 7), lower left-hand contact of sequence switch spring 115, conductor 116, upper right-hand contact of sequence switch spring 117, conductors 101 and 102, right-hand armature and front contact of relay 74, to ground for moving this sequence switch out of position 1 and into position 2.

In position 2 of sequence switch 114, a circuit is completed from grounded battery, power magnet of sequence switch 106, lower right-hand contact of sequence switch spring 107, conductor 118, left-hand armature and back contact of relay 119, conductor 120, upper contact of sequence switch spring 121, to ground, for moving this sequence switch out of position 2 and into position 3.

A circuit is now completed from grounded battery, winding of line relay 122 (Fig. 1), upper left-hand and lower right-hand contacts of sequence switch spring 123, conductor 124, contacts 44 and 37, conductor 125, lower right-hand contact of sequence switch spring 126, conductors 101 and 102, right-hand armature and front contact of relay 74, to ground. Relay 122 is energized and completes a circuit from grounded battery, power magnet of sequence switch 32, conductor 127, lower right-hand contact of sequence switch spring 128, left-hand armature and front contact of relay 122, to ground, for moving this sequence switch out of position 2 and into position 3.

In position 3 of sequence switch 106, a circuit is completed from a signaling apparatus, indicated generally at 129 (Fig. 3), left-hand contacts of sequence switch spring 75, to conductor 83, and then over the line cir-

cuit through the subscriber's substation apparatus and returning to ground over the circuit traced for line relay 80. This signal in the subscriber's receiver will inform him that the apparatus is now in readiness for him to start sending sets of impulses to set the registers shown in Figs. 5 and 6.

The selector switches used in establishing a connection are of the type whose structure and mode of operation is similar to that of the switches shown in Patent No. 1,168,319, issued January 18, 1916, to A. E. Lundell. These switches are each of five hundred line capacity. In the present arrangement, registers are provided which will be set in accordance with impulses sent out by the calling subscriber, these impulses being transmitted on a decimal basis in accordance with the digits of the number of the called subscriber. The registers will then translate these impulses to control the selective operations of the switches on a non-decimal basis. As shown in the present disclosure, provision is made to have a call extended through four switches, each of five hundred lines capacity. In accordance with the well-known grouping arrangement, by means of the latter two switches of the train 10,000 lines may be served. Therefore, the first two switches of the train will be utilized to select an office of 10,000 line capacity. The first switch of the train will select a district office and the second switch of the train will then be operated to select a particular office. By varying the number of trunk lines in a group at the district and office selector switches, an exchange capacity ranging from 4,000,000 to 10,000,000 lines may be obtained. For instance, if each brush of the district selector has access to four groups of twenty-five trunks each, any one of twenty districts may be selected by the district selector with twenty-five trunk lines running to each district. If the grouping arrangement at the office selector is the same, any one of twenty offices may be selected by the office selector. Therefore, connection may be extended by means of a district selector and an office selector to any one of four hundred offices, each one of 10,000 line capacity. This would provide a system of 4,000,000 lines. If each of the brushes at the district selector has access to ten groups of trunks of ten lines each, a call may be extended to any one of fifty districts, and if the office selector grouping arrangement is the same, the call may then be further extended to any one of fifty offices by means of an office selector, so that a call may be extended by means of a district selector and an office selector to any one of twenty-five hundred offices, each of 10,000 line capacity. As a result, this grouping arrangement would provide an exchange system of 25,000,000 line capacity. The trunk layout would be dependent upon traffic conditions

and since the particular number of trunks per group is immaterial in the present arrangement, no specific grouping will be described for the district and office switches. At the incoming switch, which is the third 70 switch in the train, each of the five brushes of the selector has access to four groups of twenty-five trunk lines each, each of these trunk lines terminating in a final connector switch. At the final connector switch each 75 of the five brushes has access to ten groups of ten lines each, each of these lines leading to a subscriber's station.

In order that the calling subscriber may not have to carry in mind a large number of digits, it is proposed to designate the desired office number by means of letters of the alphabet and three series of impulses will be sent to set three registers to control the first two switches of the train. These three registers will control brush and group selection at the district selector and brush and group selection at the office selector. An impulse sending device of any well-known type will be used, being arranged merely to cause a 80 desired number of circuit interruptions in response to the operation of a finger wheel. The sender dial might be lettered so that in addition to a finger hold for each digit, the hold characterized by the No. 0, which would 85 be arranged to send one impulse, may also bear the letter "A." The No. 1 finger hold may bear the characterization "B" and 1. In this way the lettering on the dial plate complete would be A—0, B—1, C—2, D—3, 90 E—4, F—5, G—6, H—7, I—8, J—9.

It will be assumed that the calling subscriber desires to establish connection to a subscriber whose number is 6843 in an office characterized by the three letters J—J—E. 105 The subscriber will therefore first operate his impulse dial to send ten impulses, then to send ten more impulses and then to send five impulses, after which he will proceed to send the digits constituting the desired number in the selected office.

In response to the first series of impulses, the circuit of line relay 80 is intermittently interrupted. Relay 98 being slow to release remains energized during the sending of the 115 impulses, in spite of the fact that its circuit is intermittently broken at the armature and front contact of relay 80. With the first deenergization of relay 80, a circuit is completed from grounded battery, 120 right-hand armature and back contact of relay 130, lower right-hand contact of sequence switch spring 131, conductor 132, upper contacts of register spring 133, conductor 134, left-hand winding of relay 135, 125 conductor 136, armature and back contact of relay 80, conductors 113 and 102, right-hand armature and front contact of relay 74, to ground.

In order that the setting operation of the 130

- registers may be understood, it is understood that all the register contact springs designated by the letters B, F and G are so arranged that in the odd positions of the 5 register switch with which they are associated, the upper contacts will be closed, while in the even positions of the switch the lower contacts will be closed. In each case the normal position of the switch will be 10 considered as an odd position.
- Relay 135 is energized in the above traced circuit and completes a circuit from grounded battery, power magnet of register 137, upper contact of register spring 138 (the upper contact being closed, since the 15 register is in its normal position), conductor 139, lower right-hand contact of sequence switch spring 140, left-hand armature and front contact of relay 135, to ground, for moving this register out of its 20 normal position and into position 0. Relay 135 upon energization also completes two locking circuits for itself by way of its right-hand armature. The first of these extends from grounded battery, right-hand armature and front contact of relay 135, left-hand winding of relay 135, conductor 136, armature and back contact of relay 80, to ground over the path described, and 25 maintains this relay energized until line relay 80 is energized in response to the completion of the first interruption of the line circuit. The second locking circuit of relay 135 extends from grounded battery, right-hand armature and front contact of relay 135, right-hand winding of relay 135, conductor 141, upper contacts of register spring 142, conductor 143, upper left-hand contact 30 of sequence switch spring 144, to ground.
- 40 The locking circuit through the right-hand winding of relay 135 is broken as soon as register 137 moves into an even position due to opening of the circuit at the upper contacts of spring 142. When the line circuit 45 is again completed and relay 80 energized, the circuit through the left-hand winding of relay 135 is broken and the relay de-energizes. In response to the next deenergization of relay 80, with the register 137 in 50 position 0, a circuit is completed from grounded battery, right-hand armature and back contact of relay 135, upper left-hand contact of sequence switch spring 145, conductor 146, lower contacts of register spring 142, conductor 147, left-hand winding of relay 130, conductor 136, armature and back contact of relay 80, to ground, over the path 55 described. Relay 130 is energized and completes a circuit from grounded battery, power magnet of register 137, lower contact of register spring 138, conductor 148, upper left-hand contact of sequence switch spring 149, conductor 150, left-hand armature and front contact of relay 130, to 60 ground, for moving the register out of position 65

sition 0 and into position 1. Relay 130 upon energization completes two locking circuits for itself through its right-hand armature, one of these circuits extending from grounded battery, right-hand armature and front contact of relay 130, right-hand winding of relay 130, conductor 151, lower contacts of register spring 133, conductor 143, upper left-hand contact of sequence switch spring 144, to ground. The other locking circuit 70 extends from grounded battery, right-hand armature and front contact of relay 130, left-hand winding of relay 130, conductor 136, armature and back contact of relay 80, to ground over the path previously described. As before, when the line circuit is again closed, the resultant energization of relay 80 opens the locking circuit through the left-hand winding of relay 130 and the moving of relay 137 out of position 0 and 80 into position 1 will open the circuit through the lower contacts of register spring 133 and relay 130 deenergizes. In response to the third interruption of the line circuit, relay 135 is energized to advance register 85 137 out of position 1 and into position 2, over circuits identical with those previously traced for moving the register out of its normal position and into position 0. Locking circuits for relay 135 identical with 90 those previously described in the description of the operation of this relay are also completed and broken in the same manner. In response to the fourth interruption of the line circuit, relay 130 is again energized 95 to move register 137 from position 2 to position 3 in the same manner as described for moving it from position 0 to position 1, the cycle of operation of relay 130 in this case being the same as when it was previously brought into use. It will thus be seen 100 that for each interruption of the line circuit, the register 137 will be advanced one position. At the termination of the first series of impulses, at which time ten interruptions of the line circuit will have occurred, the register 137 will have advanced ten steps into position 9. Relay 130 is energized in response to the last deenergization of line relay 80. 105

110 It is to be observed that as soon as register 137 left its normal position, a circuit was completed for relay 119 (Fig. 4), this circuit extending from grounded battery, winding of relay 119, lower contact of sequence switch spring 152, conductor 153, contact of register spring 154, lower contacts of register springs 155, 156, 157, 158, 159, 160 in series, conductor 161, armature and front contact of relay 80, to ground, as described. 115 This circuit is completed momentarily each time that relay 80 is energized during the sending of the first series of impulses. Relay 119 is, however, designed to be slow to pull up its armatures and therefore these 120 125 130

momentary circuit closures will not allow it to attract its armatures. However, after register 137 has been positioned and during the interval between the sending of the first 5 and second series of impulses, relay 80 remains energized for a relatively long time and as a result relay 119 attracts its armatures. Relay 119 at its right-hand armature completes a circuit from grounded battery, 10 power magnet of sequence switch 106, lower left-hand contact of sequence switch spring 107, conductor 162, right-hand armature and front contact of relay 119 to ground, for moving this sequence switch out of position 15 3 and into position 4. When sequence switch 106 leaves position 3, the energizing circuit of relay 119 is broken at the lower contact of sequence switch spring 152, and relay 119 deenergizes, thus opening the driving circuit of sequence switch 106 to prevent 20 this sequence switch from moving through more than one position.

In position 4 of sequence switch 106 the second series of impulses may be received. 25 Ten impulses will be sent to advance register 163 ten steps into position 9. At this time relays 130 and 135 function to control the advance of register 163 in a manner substantially similar to that previously described. 30 At this time, however, the energizing circuit for relay 135 extends through the upper right-hand contact of sequence switch spring 131, through the upper contacts of register spring 164 and then by way of conductor 35 134, as previously described. The energizing circuit of relay 130 extends by way of the upper right-hand contact of sequence switch spring 145 and the lower contacts of sequence switch spring 165 and thence by 40 way of conductor 147 through the winding of relay 130 and to ground, as described. Since the operation of setting register 163 is fundamentally similar to that of setting register 137, it is thought that it need not be 45 described in detail. It is to be observed that after the second series of impulses has been sent relay 80 will remain energized a comparatively long time and will complete a circuit for relay 119 which may be traced 50 from grounded battery, winding of relay 119, upper right-hand contact of sequence switch spring 152, conductor 166, upper contact of register spring 155, through the lower contacts of register springs 156, 157, 55 158, 159, 160 in series, conductor 161, armature and front contact of relay 80 to ground, as described. This circuit has been intermittently closed upon each short actuation of relay 80, but does not become effective 60 until after the sending of the series of impulses. When relay 119 is energized, a circuit is completed from grounded battery, power magnet of sequence switch 106, lower left-hand contact of sequence switch spring 65 107, conductor 162, right-hand armature and

front contact of relay 119, to ground, for moving this sequence switch out of position 4 and into position 5.

The subscriber continues sending the complete number of sets of impulses and as a result 70 register 167 will be set in position 4, register 168 will be set in position 6, register 169 will be set in position 8, register 170 will be set in position 4, register 171 will be set in position 3. Upon the completion of 75 the setting of register 167, the energization of relay 119 will advance switch 106 from position 5 to position 6, the completion of the setting of register 168 will advance sequence switch 106 into position 7, the completion of the setting of register 169 will advance sequence switch 106 into position 8, 80 the completion of the setting of register 170 will advance sequence switch 106 into position 9, and when the last register 171 85 is positioned, sequence switch 106 will be advanced out of position 9 and into position 10. Relay 119 is held energized in position 10 due to a circuit from grounded battery, winding of relay 119, upper left-hand 90 contact of sequence switch spring 152, right-hand armature and front contact of relay 119, to ground.

When sequence switch 106 has reached position 5, at which time registers 137 and 95 163 will have been positioned, these being the registers that control the operation of the selector switch indicated in Fig. 1, the selective operation of this switch is started. A circuit is completed from grounded battery, 100 winding of relay 122 (Fig. 1), upper contacts of sequence switch spring 123, conductors 172 and 173, contacts 45 and 38, conductor 174, winding of polarized overflow relay 175, armature and back contact of the 105 0' counting relay, winding of stepping relay 176, upper contact of sequence switch spring 177, conductor 178, right-hand armature and front contact of relay 98, inner left-hand armature and back contact of relay 110 82, lower left-hand contact of sequence switch spring 126, conductor 125, contacts 37 and 44, conductor 124, lower right and upper left-hand contacts of sequence switch spring 179, resistance 180, conductor 181, lower 115 right-hand contact of sequence switch spring 182, upper right-hand contact of sequence switch spring 183, to ground. Relay 122 is energized in this circuit and locks itself to conductor 173 by way of its right-hand armature and front contact. At its left-hand armature, relay 122 completes a circuit from grounded battery, power magnet of sequence switch 32, conductor 127, lower right-hand contact of sequence switch spring 128, 120 125 left-hand armature and front contact of relay 122, to ground, for moving this sequence switch out of position 3 and into position 4.

It is to be noted that relays 175 and 176 are included in the above traced energizing 130

- circuit for relay 122. Relay 175 is polarized and does not energize in this circuit. Stepping relay 176 is, however, energized in this circuit and completes a circuit from ground, 5 armature and front contact of relay 176, upper left-hand contact of sequence switch spring 184, conductor 185, upper left-hand contact of register spring 186, conductor 187, armature and back contact of the No. 4' counting relay, winding of the No. 4 counting relay, to grounded battery. The No. 4 counting relay is energized and prepares a circuit for the No. 4' counting relay in the well-known manner, the energization of the 10 No. 4' counting relay being subject to the deenergization of the stepping relay 176, as is well-known in the art.
- In position 4 of sequence switch 32 and with relay 122 energized, a circuit is completed from grounded battery, winding of updrive magnet 188, upper contacts of sequence switch spring 189, left-hand armature and front contact of relay 122, to ground. The brush-carrying shaft 190 is 15 moved upward under the control of magnet 188 to position one of the brush sets carried thereby in readiness to be tripped. As the brush rod 190 moves upward, a brush 191 is brought into engagement with a conducting segment of a commutator 192. As soon as the brush 191 engages a conducting segment of commutator 192, the stepping relay 176 is shunted out over a path extending from grounded battery, winding of relay 20 122, right-hand armature and front contact of relay 122, conductor 172, upper right-hand contact of sequence switch spring 123, conductor 193, upper contact of sequence switch spring 194, conductor 195, commutator 192, brush 191, conductor 196, lower left-hand contact of sequence switch spring 197, to ground. As a result of this shunting action, relay 176 is deenergized and allows the No. 4' counting relay to be energized 25 due to a circuit being closed from grounded battery, windings of No. 4 and No. 4' counting relays, armature and front contact of No. 4 counting relay, contact of sequence switch spring 246, conductor 247, upper left-hand contact of sequence switch spring 245 to ground. Counting relays are now successively actuated in response to the advance of brush 191, and when the No. 0' counting relay is energized, at which time the brush 30 shaft will have been advanced into a position where the fifth brush set may be tripped into operative relation with the section of the contact bank served by it, the lower branch of the fundamental circuit will be open; and when a moment later brush 191 engages an insulating segment of commutator 192, the circuit of relay 122 is broken. Relay 122 deenergizes and completes a circuit from grounded battery, power magnet 35 of sequence switch 32, conductor 127, upper

right-hand contact of sequence switch spring 128, left-hand armature and back contact of relay 122, to ground, for moving this sequence switch out of position 4 and into position 5.

At the sender a relay 198 is energized in parallel with the No. 0' counting relay due to a circuit being closed from grounded battery, winding of No. 0 counting relay, windings of relays No. 0' and 198 in parallel, 70 armature and front contact of No. 0 counting relay, contact of sequence switch spring 246, conductor 247, upper left-hand contact of sequence switch spring 245 to ground. Upon the energization of relay 198 a circuit 75 is completed from grounded battery, power magnet of sequence switch 114, upper right-hand contact of sequence switch spring 115, armature and front contact of relay 198 to ground, for moving this sequence switch out 80 of position 2 and into position 3. As soon as the sequence switch leaves position 2, the holding circuits of the counting relays are opened at contacts 243 and 246. Sequence switch 114 is immediately moved out of position 85 3 and into position 4 by means of a circuit extending from grounded battery, power magnet of sequence switch 114, upper right-hand contact of sequence switch spring 199, conductor 200, upper right-hand 90 contact of sequence switch spring 97, to ground, it being assumed that sequence switch 106 will have by this time advanced at least as far as position 7 in response to the successive setting of the various registers.

As soon as sequence switch 32 reaches position 4, a circuit is completed from grounded battery, winding of trip magnet 201, upper right-hand contact of sequence 105 switch spring 202, lower left-hand contact of sequence switch spring 197, to ground. The energization of magnet 201 operates a trip rod 203 so that upon subsequent upward movement of brush rod 190, the fifth set of 110 brushes will be tripped.

As soon as sequence switch 114 reaches position 4 and sequence switch 32 reaches position 5, a circuit is completed from grounded battery, winding of relay 122, upper contacts of sequence switch spring 123, conductors 172 and 173 to ground over the path previously described. Relay 122 is energized and locks itself to conductor 173 and at its left-hand armature completes a 120 circuit from grounded battery, power magnet of sequence switch 32, conductor 127, lower right-hand contact of sequence switch spring 128, left-hand armature and front contact of relay 122, to ground, for moving 125 this sequence switch out of position 5 and into position 6. As before, the energizing circuit of relay 122 includes the stepping relay 176, and at this time the energization of relay 176 completes a circuit from ground, 130

5 armature and front contact of relay 176, upper right-hand contact of sequence switch spring 184, conductor 204, upper contact of register spring 205, upper left-hand contact of register spring 206, conductor 207, 70 armature and back contact of the No. 7 counting relay, winding of the No. 7 counting relay, to grounded battery. The No. 7 counting relay is energized and prepares a 10 circuit for the No. 7' counting relay in the well-known manner.

In position 6 of sequence switch 32 and with relay 122 energized, a circuit is completed from grounded battery, winding of 15 updrive magnet 188, upper contacts of sequence switch spring 189, left-hand armature and front contact of relay 122, to ground. The brush rod 190 is again moved upwardly to advance the fifth set of brushes 20 in a group-selecting movement. At this time when commutator brush 209 engages the conducting segment of commutator 210, the stepping relay 176 is shunted out by a circuit traceable from grounded battery, 25 winding of relay 122, right-hand armature and front contact of relay 122, upper right-hand contact of sequence switch spring 123, conductor 193, lower contact of sequence switch spring 194, conductor 211, commutator 210, brush 209, conductor 196, lower 30 left-hand contact of sequence switch spring 197, to ground. Stepping relay 176 is deenergized and allows the No. 7' counting relay to energize. The counting relays are 35 successively actuated in response to the intermittent shunting out of stepping relay 176, and when the No. 0' counting relay and relay 198 are energized, the lower branch of the locking circuit of relay 122 is broken; 40 and when a moment later brush 209 engages an insulating segment of commutator 210, relay 122 is deenergized. A circuit is then completely from grounded battery, power magnet of sequence switch 32, conductor 127, 45 upper right-hand contact of sequence switch spring 128, left-hand armature and back contact of relay 122, to ground, for moving this sequence switch out of position 6 and into position 7.

50 The energization of relay 198 completes a circuit from grounded battery, power magnet of sequence switch 114, upper right-hand contact of sequence switch spring 115, armature and front contact of relay 198, to ground, for moving this sequence switch out of position 4 and into position 5. Sequence switch 114 is then moved out of position 5 and into position 6 by means of a circuit extending from grounded battery, power magnet of sequence switch 114, lower contact of sequence switch spring 363, conductor 364, lower contact of sequence switch spring 365, to ground, provided the sequence switch 106 has reached position 7 at this time.

55 The selected brush set has now been ad-

vanced to a position such that the brushes are engaging the lowermost set of terminals in the seventh group of terminals served by this brush set. Busy trunk lines are characterized by the presence of ground potential on their test terminals. It will be assumed that the lowermost trunk in the group is busy.

In position 7 of sequence switch 32, a circuit is completed from grounded battery, 75 left-hand winding of relay 212, lower right-hand contact of sequence switch spring 213, left-hand armature and back contact of relay 122, to ground. Relay 212 is energized and completes a locking circuit for itself 80 from grounded battery, right-hand winding of relay 212, lower contacts of sequence switch spring 274, outermost armature and front contact of relay 212, conductor 215, to test brush 216. Since it has been assumed 85 that the first trunk in the selected group is busy, ground potential on such terminal will maintain relay 212 energized. As soon as relay 212 is energized, a circuit is completed from grounded battery, power magnet of 90 sequence switch 32, conductor 127, lower right-hand contact of sequence switch spring 128, inner armature and front contact of relay 212, to ground, for moving this sequence switch out of position 7 and into position 8. 95

In position 8 of sequence switch 32, a circuit is completed from grounded battery, winding of updrive magnet 188, lower contacts of sequence switch spring 202, inner armature and front contact of relay 212, to 100 ground. The selected brush set is now advanced in a trunk-hunting movement, and when the test brush 216 encounters a test terminal 217 to which no ground is connected, the locking circuit through the right-hand winding of relay 212 is broken. Relay 212 is, however, maintained energized a moment longer by means of a circuit extending from grounded battery, through its 105 left-hand winding, upper right-hand contact of sequence switch spring 213, conductor 218, commutator 219, brush 220, lower left-hand contact of sequence switch spring 202, right-hand armature and front contact of relay 212, to ground. As soon as brush 110 220 engages an insulating segment of commutator 219, at which time the brush set will be accurately centered on the terminals of the desired trunk line, relay 212 is deenergized and opens the circuit of magnet 115 188 to allow the brush set to be brought to rest. The deenergization of relay 212 completes a circuit from grounded battery, power magnet of sequence switch 32, conductor 127, lower left-hand contact of sequence switch spring 128, inner armature and back contact of relay 212, to ground, 120 for moving this sequence switch out of position 8 and into position 10.

125 A fundamental circuit is now completed 130

from grounded battery at the office selector associated with the seized trunk, over conductor 230, terminal 234, brush 231, lower contact of sequence switch spring 232, conductors 233 and 173, contacts 45 and 38, conductor 174, relay 175, armature and back contact of No. 0' counting relay, winding of stepping magnet 176, upper contact of sequence switch spring 177, conductor 178, 5 upper contact of sequence switch spring 126 (it being assumed that the sequence switch 106 has reached its seventh position), conductor 125, contacts 37 and 44, conductor 124, lower contact of sequence switch spring 15 235, brush 236, terminal 237 to ground at the office selector. Through any appropriate means at the office selector, the switch power magnet will energize and brush selection will take place in substantially the same 20 manner as that described in connection with the district selector. The office selector in its movement will cause interruptions of the flow of current to the stepping relay 176 by means of an interrupter corresponding to 25 the commutator 192 and brush 191 at the district selector.

The closure of the fundamental circuit causes the energization of relay 176. Upon the energization of the stepping relay 176, 30 a circuit is completed from ground, armature and front contact of relays 176, lower contact of sequence switch spring 184, lower contact of register spring 249, lower contact of register spring 250, upper contact 35 of register 251, conductor 187, right-hand armature and back contact of No. 4' counting relay, winding of No. 4 counting relay to grounded battery. The No. 4 counting relay prepares a circuit for the No. 4' counting relay in the same manner as above described. The movement of the office selector operates the counting relays in the well-known manner until the No. 0' counting relay and relay 198 are energized. The No. 45 0' counting relay opens the fundamental circuit, thus ending the first cycle of operations and stopping the office selector in a position to trip the fifth set of brushes.

The energization of relay 198 closes the 50 circuit from grounded battery, power magnet of sequence switch 114, upper right-hand contact of sequence switch spring 115, armature and front contact of relay 198 to ground for moving the sequence switch out of position 55 6 and into position 7. Sequence switch 114 immediately moves out of position 7 and into position 8, due to a circuit being closed from grounded battery, power magnet of sequence switch 114, lower contact of sequence switch spring 363, conductor 364, lower contact of sequence switch spring 365 to ground. In passing from position 6 to position 8, the sequence switch 114 interrupts at contacts 60 243 and 246 the holding circuits of the 65 counting relays.

In position 8 of the sequence switch 114, the fundamental circuit is again closed through to the office selector and again causes the energization of the updrive magnet at the office selector. Group selection at 70 the office selector will now take place. As the switch shaft is elevated, the current through the stepping relay 176 will be shunted by means of a shunt circuit through a commutator similar to the commutator 210 75 at the district selector. The first energization of the stepping relay 176 completes a circuit from ground, armature and front contact of relay 176, upper left-hand contact of sequence switch spring 255, conductor 80 256, lower contact of register spring 257, upper contact of register spring 258, lower left-hand contact of register spring 252, conductor 208, armature and back contact of No. 3' counting relay, winding of No. 3 counting 85 relay to grounded battery. The counting relays will be actuated in the same manner as above described.

As soon as the No. 0' counting relay is energized, the fundamental circuit is opened, 90 thus stopping the selected set of brushes of the office selector at the bottom of the fourth group of terminals served thereby. The brushes of the selected set at the office selector will now be caused to hunt for the terminals associated with an idle incoming selector in the selected group. 95

Upon the energization of relay 198, the above traced circuit for power magnet sequence switch 114 will be closed for moving 100 this sequence switch out of position 8 and into position 9. The holding circuit of the counting relays is interrupted at contacts 243 and 246 as before.

As soon as the office selector has seized 105 a trunk leading to an idle incoming selector and sequence switch reaches position 9, the fundamental circuit will again be closed over the circuit above described from conductor 174 then through resistance 259, 110 winding of relay 260, lower contact of sequence switch spring 177, conductor 178 to ground at the incoming selector. Relay 260 becomes energized and completes, if sequence switch 106 has reached position 10, a circuit 115 from grounded battery, power magnet of sequence switch 114, upper contacts of sequence switch spring 115, armature and front contacts of relay 260 to ground over conductor 262 for moving this sequence 120 switch out of position 9 and into position 10. In position 10, the circuit through relay 260 is opened at the lower contact of sequence switch spring 177 and the fundamental circuit is again closed through relay 176. 125 Upon the energization of relay 176, a circuit is closed from ground, armature and front contact of relay 176, upper right-hand contact of sequence switch spring 255, conductor 460, upper right-hand contact of regis 130

ter spring 261, conductor 208, armature and back contact of No. 3' counting relay, winding of No. 3 counting relay to grounded battery. Brush selection at the incoming selector now takes place and as the switch is elevated, the stepping relay 176 is deenergized and the counting relays actuated in the same manner as above described. As soon as the No. 3' counting relay is energized the fundamental circuit is opened, thus terminating the first cycle of operations or the brush selection at the incoming selector. With the switch in a position to trip the fourth set of brushes upon the energization of relay 198, the above described circuit for the power magnet sequence switch 114 is closed for moving this sequence switch out of position 10 and into position 11. The sequence switch 114 is immediately moved out of position 11 and into position 12 due to a circuit from grounded battery, power magnet of sequence switch 114, lower left-hand contact of sequence switch spring 199, conductor 262, lower right-hand contact of sequence switch spring 245 to ground.

As soon as the sequence switch 114 leaves position 10, the holding circuits for the counting relays are opened at contacts 243 and 246 as before. When the sequence switch 114 reaches position 12, the fundamental circuit is again closed through to the incoming selector. This causes the operation of the incoming selector switch power magnet and connects an interrupter, similar to commutator 210 of the district selector, in shunt with the fundamental circuit. Group selection at the incoming selector now takes place. Upon the energization of relay 176, a circuit is closed from ground, armature and front contact of relay 176, lower right-hand contact of sequence switch spring 255, conductor 263, lower contact of sequence switch spring 264, upper contact of register spring 265, conductor 461, armature and back contact of No. 1' counting relay, winding of No. 1 counting relay to grounded battery. As the incoming selector is operated, the counting relays will be actuated in the same manner as above described.

The energization of No. 0' counting relay opens the fundamental circuit, thus terminating the group selection at the incoming selector. The incoming selector will now automatically hunt for a trunk leading to an idle final selector. Upon the energization of relay 198 the above described circuit for the power magnet of sequence switch 114 is closed and moves this sequence switch out of position 12 and into position 13. This sequence switch is immediately moved out of position 13 and into position 14, due to the circuit previously described through the lower left-hand contact of sequence switch 199.

As soon as the incoming selector has seized a trunk leading to an idle final selector and the sequence switch 114 reaches position 14, the fundamental circuit is again closed and brush selection takes place at the final selector. Upon the closing of the fundamental circuit, relay 176 is again energized and completes a circuit from ground, armature and front contact of relay 176, lower left-hand contact of sequence switch spring 255, conductor 266, lower right-hand contact of sequence switch spring 267, conductor 208, armature and back contact of No. 3' counting relay, winding of No. 3 counting relay to grounded battery. The counting relays are actuated in the same manner as above described until the counting relay No. 0' and relay 198 are energized. No. 0' counting relay interrupts the fundamental circuit, thus terminating the brush selection at the final selector with the switch in a position to trip its fourth set of brushes. The energization of relay 198 closes the above traced circuit for the power magnet of sequence switch 114 to move this sequence switch out of position 14 and into position 15. This sequence switch is immediately moved out of position 15 and into position 16, due to the above traced circuit through the lower left-hand contact of sequence switch spring 199. As soon as the sequence switch 114 leaves position 14, the holding circuits for the counting relays are interrupted at the sequence switch springs 243 and 246.

When the sequence switch 114 reaches position 16, the fundamental circuit is again closed and tens selection now takes place at the final selector. Upon the energization of relay 176, a circuit is completed from ground, armature and front contact of relay 176, upper left-hand contact of sequence switch spring 268, conductor 269, upper right-hand contact of register spring 270, conductor 187, armature and back contact of No. 4' counting relay, winding of No. 4 counting relay to grounded battery. The counting relays are actuated in the same manner as above described until the No. 0' counting relay and relay 198 are energized. The energization of the No. 0' counting relay interrupts the fundamental circuit, thus terminating the group selection of the final selector with the selected set of brushes at the bottom of the fifth group of terminals in which the called subscriber's line terminals are located. The energization of relay 198 closes the above traced circuit for the power magnet of sequence switch 114 by moving this sequence switch out of position 16 and into position 17. This sequence switch is immediately moved out of position 17 and into position 18, due to the above traced circuit through the lower left-hand contact of sequence switch spring 199. As

soon as the sequence switch 114 leaves position 16, the holding circuits for the counting relays are opened at the sequence switch springs 243 and 246.

- 5 When the sequence switch 114 reaches position 18, the fundamental circuit is again closed and units selection at the final selector takes place. Upon the energization of relay 176, a circuit is closed from ground, 10 armature and front contact of relay 176, upper right-hand contact of sequence switch spring 268, conductor 271, lower right-hand contact of register spring 272, conductor 208, armature and back contact of No. 3' counting relay, winding of No. 3 counting relay to grounded battery. The counting relays are actuated in the same manner as above described until the selected set of brushes of the final selector has engaged the fourth 15 set of terminals in the selected group, at which time the counting relay No. 0' and the relay 198 become energized. The energization of counting relay 0' opens the fundamental circuit, thus stopping the selected 20 set of brushes of the final selector on the terminals of the called line. Ringing current will now be applied to the called line at the incoming selector in the well-known manner. 25 Upon the energization of relay 198, a circuit is closed from grounded battery, power magnet of sequence switch 106, lower right-hand contact of sequence switch spring 107, conductor 118, left-handed armature and 30 front contact of relay 119, which is energized at this time in the manner previously described, conductor 380, upper right-hand contact of sequence switch spring 290, armature and front contact of relay 198 to 35 ground, for moving sequence switch 106 out of position 10 and into position 12. A circuit is now closed from grounded battery, left-hand winding of relay 212, Fig. 1, lower left-hand contact of sequence switch spring 40 213, conductor 291, contacts 43 and 36, conductors 292 and 293, lower contact of sequence switch spring 117, right-hand armature and front contact of relay 74, to ground. Relay 212 becomes energized and completes 45 a circuit from grounded battery, power magnet of sequence switch 32, conductor 127, lower right-hand contact of sequence switch spring 128, inner armature and front contact of relay 212 to ground, by moving this 50 sequence switch out of position 10 and into position 12.

In position 11 of sequence switch 32, a circuit is completed from grounded battery, winding of relay 29 (which became deenergized when sequence switch 32 left position 4), lower right-hand contact of sequence switch spring 30, left-hand armature and back contact of relay 31, terminal 28, brush 23, right-hand winding of relay 24, outer 55 armature and front contact of relay 24, off-

normal contact 13, right-hand and left-hand windings of relay 70, winding of cutoff relay 11 to ground. This circuit is maintained until sequence switch 32 reaches position 16.

As soon as the sequence switch 32 leaves position 11, the holding circuit of relay 74 is opened at the upper contact of sequence switch spring 30, but this relay is still held energized, due to a circuit being closed from conductor 79, lower contacts of sequence switch spring 189, conductor 173, contacts 45 and 38, conductor 174, upper left-hand and lower right-hand contacts of sequence switch spring 293, conductor 294, resistance 295, lower right-hand contact of sequence switch spring 111 to ground. Since the relay 74 is still energized, the above traced circuit of relay 212 is also held closed and causes sequence switch 32 to move out of position 12, through position 13, and into 35 position 14. When sequence switch 32 leaves position 11, a new holding circuit for magnet 66 is completed through conductor 71, right-hand contacts of sequence switch spring 327, conductor 291 to ground over 90 the circuit described for relay 212.

As soon as sequence switch 32 leaves position 13 $\frac{1}{2}$, a circuit is closed from grounded battery, lower left-hand winding of repeating coil 297, winding of supervisory relay 298, lower right-hand contact of sequence switch spring 88, terminal 89, brush 25, inner lower armature and front contact of relay 11, loop of the calling substation, upper armature and front contact of relay 11, 100 brush 26, terminal 90, upper contact of sequence switch spring 91, upper left-hand winding of repeating coil 297, to ground. Relay 298 becomes energized at this time. In position 14 the sequence switch springs 105 232 and 235 by engaging their up contacts connect both sides of the outgoing trunk together through the right-hand windings of repeating coil 297 and the winding of relay 309. Ringing current will now be applied to the called line at the incoming selector in the well-known manner. 110

As soon as the sequence switch 32 leaves position 13, the holding circuit of relay 74 is opened at the lower contacts of sequence 115 switch spring 189, thereby causing the deenergization of relays 74 and 212 and magnet 66. The deenergization of magnet 66 releases the line bar 42 to its normal position, while the deenergization of relay 74 120 closes a circuit from grounded battery, power magnet of sequence switch 106, upper right-hand contact of sequence switch spring 296, right-hand armature and back contact of relay 74, to ground for moving this sequence switch out of position 12 and into position 15.

The circuit for relay 98 is also interrupted at the right-hand armature and front contact of relay 74. When the sequence switch 130

32 leaves position 18½, the circuit of relay 80 is opened at the lower left-hand contact of sequence switch spring 88 and at the lower right-hand contact of the sequence switch spring 91.

The deenergization of relay 98 completes a circuit from grounded battery, power magnet of sequence switch 103, upper contact of sequence switch spring 104, left-hand armature and back contact of relay 98, to ground by moving the sequence switch out of position 2, through position 18 to its normal position.

When the sequence switch 106 reached position 12, a circuit was completed from grounded battery, power magnet of register 171, upper contact of register spring 298, conductor 299, lower contact of sequence switch spring 97, to ground by moving this register back to its normal position. As soon as the register 171 reaches its normal position a circuit is completed from grounded battery, power magnet of register 170, upper contact of register spring 300, lower contact of register spring 298, to ground over the circuit previously described.

In a similar manner, registers 169, 168, 167, 163 and 137 are successively moved into their normal positions.

As soon as all of these registers reach their normal positions, a circuit is closed from grounded battery, power magnet of sequence switch 106, lower contact of sequence switch spring 296, conductor 301, lower contacts of register springs 302, 303, 304, 305, 306, 300 and 298 in series, conductor 299, lower right-hand contact of sequence switch spring 97, to ground, for moving this sequence switch out of position 15 and into position 16. Sequence switch 106 is moved out of position 16 and into position 17 due to a circuit completed from grounded battery, power magnet of sequence switch 106, upper left-hand contact of sequence switch spring 196, lower right-hand contact of sequence switch spring 341 to ground. As soon as the sequence switch 106 reaches position 17 it is immediately moved into position 18 due to a circuit completed from grounded battery, power magnet of sequence switch 106, upper left-hand contact of sequence switch spring 107, outer left-hand armature and back contact of relay 82 to ground. A circuit is now closed from grounded battery, power magnet of sequence switch 114, lower right-hand contact of sequence switch spring 199, conductor 307, lower left-hand contact of sequence switch spring 245, to ground for moving this sequence switch out of position 18 and into position 1.

As soon as the sequence switch 114 reaches position 1, a circuit is completed from grounded battery, power magnet of sequence switch 106, lower left-hand contact of sequence switch spring 107, conductors 162

and 308, lower contact of sequence switch spring 121 to ground by moving the sequence switch 106 out of position 18 and into position 1.

As soon as the called party removes his receiver, the polarized relay 309 becomes energized in the well-known manner. A circuit is now closed from grounded battery, power magnet of sequence switch 32, lower left-hand contact of sequence switch spring 33, upper left-hand and lower right-hand contacts of sequence switch spring 310, conductor 181, armature and front contact of relay 309, upper right-hand contact of sequence switch spring 182, upper right-hand contact of sequence switch spring 183, to ground, for moving this sequence switch out of position 14 and into position 15.

A circuit is now closed from grounded battery, winding of relay 273 (Fig. 1), lower left-hand and upper left-hand contacts of sequence switch spring 179, resistance 180, armature and front contact of relay 309, upper right-hand contact of sequence switch spring 182, upper right-hand contact of sequence switch spring 183 to ground. Relay 273 becomes energized and closes a locking circuit for itself at its left-hand armature and front contact.

The subscribers are now connected for conversation. As soon as the parties are through talking, and the calling subscriber at substation 21 restores his receiver upon the switchhook, relay 298 deenergizes and completes a circuit to operate the quick acting switch shown at the left of Fig. 2. This switch is used to associate a common coin collect, coin return and metering apparatus with a connecting link taken for use. The preferred form of this switch is essentially the same in construction and operation as the switch shown and described in the above mentioned Reissue Patent No. 14,236.

In the present arrangement of the cross-bar switch there is provided for each common coin and metering apparatus, a vertical bar 286 carrying a plurality of sets of multiple contact members such as 274, 275, 276, 277, 278 and 279. For each individual connecting link there is provided a horizontal longitudinal movable bar. Each horizontal bar is provided with a plurality of sets of multiple contact members 280, 281, 282, 283, 284 and 285. Each set of these contact members is in operative relation to the contacts carried by a different vertical bar. A set magnet 288 is provided for each vertical bar and upon energization, rotates the associated vertical bar to an extent such that upon the longitudinal movement of the bar 287, the corresponding contact members will be engaged. An operating magnet 239 is provided for each horizontal bar 287. Since the construction and operation is substantially the same as that above described for

100

105

110

115

120

125

130

the common sending apparatus, it is believed that further description at this time is unnecessary.

When the sequence switch 32 reached position 14, a circuit was completed from grounded battery, right-hand winding of magnet 239, conductor 311, upper right-hand contact of sequence switch spring 182, upper right-hand contact of sequence switch spring 183, to ground. Magnet 239 is not energized at this time, since it requires that both of its windings be energized at the same instant in order to operate its associated line bar. Therefore, when the relay 298 deenergizes, due to the calling subscriber restoring his receiver upon the switchhook, the line bar is operated as at this time a circuit is closed through the left-hand winding of magnet 239, from grounded battery, armature and back contact of relay 240, left-hand winding of magnet 239, left-hand armature and back contact of relay 239, conductor 312, armature and back contact of relay 298, upper left-hand contact of sequence switch spring 72, right-hand armature and front contact of relay 29, to ground. The operation of magnet 239 causes the engagement of contacts on the bar 287 with contacts on a set vertical bar 286. The set vertical bar 286 is then released, the preselected bar set and a third bar preselected in exactly the same manner as described in connection with the common sending apparatus.

As soon as the contacts of the line bars 287 engage the contacts of the bar 286, a circuit is completed from grounded battery, winding of relays 242 and 313 in parallel, conductor 314, contact of sequence switch spring 315, conductor 316, contacts 275 and 281, conductor 317, right-hand armature and front contact of relay 273, conductor 93, upper left-hand and lower left-hand contacts of sequence switch spring 197 to ground. Relays 242 and 313 become energized and relay 313 closes a locking circuit for both relays from grounded battery, windings of both relays in parallel, left-hand armature and front contact of relay 313, upper right-hand contact of sequence switch spring 319, to ground. A circuit is also closed at this time from grounded battery, power magnet of sequence switch 241, upper right-hand contact of sequence switch spring 320, contacts 274 and 280, conductors 320 and 312, to ground over the circuit described, for moving the sequence switch 241 out of position 1 and into position 2. Another circuit is closed at this time from grounded battery, winding of relay 122, upper and lower left-hand contact of sequence switch spring 123, conductor 321, contacts 282 and 276, lower contact of sequence switch spring 319, to ground. Relay 122 becomes energized and completes a circuit from grounded battery, power magnet of sequence switch 32,

conductor 127, lower right-hand contact of sequence switch spring 128, left-hand armature and front contact of relay 122, to ground, for moving the sequence switch out of position 15 through position 16 and into 70 position 17.

As soon as the sequence switch 241 reaches position 14, a holding circuit is closed for relay 29 from grounded battery, winding of relay 29, left-hand armature and front 75 contact of relay 29, conductor 322, contacts 284 and 278, resistance 323, lower right-hand contact of sequence switch spring 319, to ground. When the sequence switch 32 reached position 16, a circuit was completed 80 from grounded battery, left-hand armature and front contact of relay 242, upper left-hand contact of sequence switch spring 324, conductor 325, contacts 277 and 283, conductor 326, left-hand contacts of sequence 85 switch spring 327, terminal 28, brush 23, right-hand winding of relay 24, outer armature and front contact of relay 24, off-normal contact 13, right-hand and left-hand windings of register magnet 70, winding of 90 cutoff relay 11, to ground. Since full potential is directly applied to the winding of relay 24, magnet 70 is energized at this time and registers the call. By attracting its armature, the magnet 70 shunts out its left- 95 hand winding.

As soon as the sequence switch 32 reaches position 17, a circuit is completed from grounded battery, power magnet of 100 sequence switch 241, upper left-hand contact of sequence switch spring 320, conductor 316, contacts 275 and 281, conductor 317, right-hand contacts of sequence switch spring 183, to ground, for moving the sequence switch 241 from position 2 to its normal position.

While the sequence switch 241 is passing through positions 2½ to 6, a circuit is completed from a source of current 330, resistance 331, contact of sequence switch spring 332, right-hand armature and front contact of relay 313, contacts 279 and 285, conductor 333, lower left-hand contact of sequence switch spring 91, terminal 90, brush 26, upper armature and front contact of cutoff 110 relay 11, polarized relay at the coin device 115 334 at the substation 21, to ground. The current in the above traced circuit is in the proper direction to cause the coin to be deposited in the coin box.

As soon as the sequence switch 241 leaves position 7, the circuit for relays 11 and 24 and magnet is opened. The deenergization of cutoff relay 11 removes the holding pawl of the distributing switch associated with the calling line and allows the brushes 23, 25 and 26 to return to their normal positions in engagement with terminals 15, 16 and 17.

As soon as the sequence switch 241 leaves position 15, relay 29 deenergizes and com- 130

pletes a circuit from grounded battery, power magnet of sequence switch 32, lower left-hand contact of sequence switch spring 33, right-hand armature and back contacts 5 of relay 29, to ground for moving this sequence switch out of position 17 and into position 18. As soon as the sequence switch 32 leaves position 17, the holding circuit of magnet 239 is opened at the upper right-hand contact of sequence switch spring 182 and the operated bar 287 is returned to its normal position.

In position 18 of sequence switch 32, a circuit is closed from grounded battery, winding 15 of downdrive magnet 335, lower contacts of sequence switch spring 197, to ground. Under the control of this magnet, the brush shaft 190 is returned to its normal position. As soon as the normal position is 20 reached, a circuit is closed from grounded battery, power magnet of sequence switch 32, upper right-hand contact of sequence switch spring 33, conductor 336, normal segment 337, brush 209, conductor 196, lower left-hand contact of sequence switch spring 197, to ground, for moving the sequence switch out of position 18 and into position 1. As soon as the brush 216 leaves the terminal 217, the office, incoming and final selector 25 switches are released in the well-known manner.

From the above description it should be observed that in case the calling subscriber completes a connection to a called line, the call is registered, the coin device at the calling substation is operated to collect the coin and also that the individual switch associated with the calling line is released as soon as the sequence switch 241 leaves position 7.

In case the called line is busy or the called party does not answer, the operation of the system is as follows: The sequence switch 32 will be in position 14 at this time so that when the calling subscriber restores his receiver, the relay 298 deenergizes and the above traced circuits for magnet 239 are completed. Magnet 239 becomes energized and connects the calling line to an idle coin and meter device in the same manner as above described. Relays 242 and 313 will not, however, energize at this time since their energizing circuit is opened at the right-hand armature and front contact of relay 273 which at this time is deenergized. As soon as the contact 280 engages contact 274, the sequence switch 241 is moved out of position 1 and into position 2 as above described. A circuit is then completed from grounded battery, winding of relay 122, 50 upper and lower left-hand contacts of sequence switch spring 123, conductor 321, contacts 282 and 276, lower left-hand contact of sequence switch spring 319 to ground. The energization of relay 122 completes a 55 circuit from grounded battery, power mag-

net of sequence switch 32, conductor 127, lower right-hand contact of sequence switch spring 128, left-hand armature and front contact of relay 122 to ground, for moving the sequence switch out of position 14 and 70 into position 17. A circuit is then completed from grounded battery, power magnet of sequence switch 241, upper left-hand contact of sequence switch spring 320, contacts 275 and 281, conductor 317, lower and 75 upper right-hand contacts of sequence switch spring 183 to ground, for moving the sequence switch 241 from position 2 to its normal position.

As soon as the sequence switch 32 leaves 80 position 16, the circuit of relay 29 is opened at the lower right-hand contact of sequence switch spring 30, but this relay is held energized by a circuit through its left-hand armature and front contact, conductor 322, 85 contacts 284 and 278, resistance 323, lower right-hand contact of sequence switch spring 319, to ground. At the same time a new circuit is completed for magnet 70 from grounded battery, resistance 342, right-hand 90 armature and back contact of relay 242, upper right-hand contact of sequence switch spring 324, conductor 325, contacts 277 and 283, conductor 326, left-hand contacts of sequence switch spring 327, terminal 28, brush 95 23, right-hand winding of relay 24, outer left-hand armature and front contact of relay 24, off-normal contact 13, right-hand and left-hand windings of magnet 70, winding of cutoff relay 11 to ground. Due to the resistance 342, the magnet 70 does not receive sufficient current to operate and register the call. While the sequence switch 241 is rotating 100 from position 8 to 10, a circuit is completed from a source of current 343, winding of relay 344, lower contact of sequence switch spring 345, right-hand armature and back contact of relay 313, contacts 279 and 285, conductor 333, lower left-hand contact of sequence switch spring 91, terminal 90, brush 110 26, upper armature and front contact of relay 11, coin device 334 to ground. The current in this circuit is in a direction to cause the polarized relay of the coin device 341 to operate and refund the coin to the calling 115 subscriber. Relay 344 becomes energized and at its left-hand armature and front contact completes a circuit for connecting the grounded battery and resistance 342 to the lower contact of sequence switch spring 324 120 for maintaining the circuit of cutoff relay closed until the polarized relay of the coin device 341 has had time to operate. When sequence switch 241 leaves position 11, the circuit of cutoff relay 11 is opened at the 125 lower contact of sequence switch spring 324. The deenergization of relay 11 causes, in the manner described, the release of the individual switch associated with the calling line. As soon as the sequence switch 241 130

leaves position 15, relay 29 deenergizes and the district selector and the other switches are released in the same manner as above described. It should be noted from the above 5 description that in case the calling subscriber is unsuccessful in obtaining a connection to a called line, the call is not registered and the coin is refunded to the calling subscriber.

It was assumed that the calling line was 10 equipped with both a coin device and a message register. The operation is exactly the same, however, in case the calling line is equipped with only a coin device. We will now assume that the calling line is not 15 equipped with a coin device and in such case relay 344 does not energize when the calling line is unsuccessful in establishing a connection, since there is no ground applied to the brush 26 at the time the source of current 342 20 is applied thereto. In this case then the circuit of the cutoff relay 11 is opened when the sequence switch 241 leaves position 8₁, whereas in case the calling line is equipped with a coin device, the cutoff relay 11 is not 25 deenergized until the sequence switch 241 reaches position 11.

We will now consider the operation of the system disclosed in case the calling subscriber abandons the call before the connection to the called line is completed. In 30 the first case it will be assumed that the calling subscriber restores his receiver before sending any impulses. At this time the sequence switch 32 will be in position 3, sequence switch 103 in position 2, sequence switch 106 in position 3 and sequence switch 114 in position 3. As soon as the calling subscriber restores his receiver upon the switchhook, relay 80 deenergizes and in turn 35 causes the deenergization of relay 98. A circuit is then closed from grounded battery, power magnet of sequence switch 103, upper contact of sequence switch spring 104, left-hand armature and back contact of relay 98 to ground, for moving the sequence switch from position 2 to its normal position. While sequence switch 103 is moved 40 from position 3 to 10, a circuit is completed from a source of current 346, winding of relay 77, lower contact of sequence switch spring 95, conductor 94, contacts 41 and 48, conductors 93 and 92, lower right-hand contact of sequence switch spring 91, terminal 90, brush 26, upper armature and front contact of relay 10, coin device 334 to ground. Current flowing in this circuit is in the proper direction to cause the polarized relay 45 at the coin device 334 to operate and refund the coin. As soon as the sequence switch 50 103 leaves position 12, the locking circuit of relay 74, register magnet 70 and cutoff relay 11 is opened at the upper right-hand contact of sequence switch spring 76. Magnet 70 deenergizes and therefore does not 55 register the call, and relay 11 releases the

calling subscriber's line from the district selector. Relay 74 deenergizes and completes a circuit from grounded battery, power magnet of sequence switch 106, upper right-hand contact of sequence switch spring 296, right-hand armature and back contact of relay 74 to ground, for moving this sequence switch out of position 3 and into position 7. A circuit is then completed from grounded battery, winding of relay 340, conductor 348, 70 upper right-hand and lower left-hand contacts of sequence switch spring 293, conductor 349, right-hand contacts of sequence switch spring 350, conductor 351, right-hand armature and back contact of relay 74 to 80 ground. Relay 340 completes a locking circuit for itself from grounded battery, winding of relay 340, right-hand armature and front contact of relay 340, upper left-hand contact of sequence switch 111 to 85 ground. Relay 340 also completes a circuit from grounded battery, power magnet of sequence switch 114, lower right-hand contact of sequence switch spring 115, conductor 352, right-hand armature and front 90 contact of relay 340, upper left-hand contact of sequence switch spring 111 to ground, moving the sequence switch out of position 2 and into position 18. A circuit is then 95 closed from grounded battery, power magnet of sequence switch 106, lower right-hand contact of sequence switch spring 107, conductor 118, left-hand armature and back contact of relay 119, conductor 120, upper contact of sequence switch spring 121 to 100 ground, for moving the sequence switch out of position 7 and into position 12. Sequence switch 106 is immediately moved out of position 12 and into position 15 due to a circuit being closed from grounded battery, 105 power magnet of sequence switch 106, upper right-hand contact of sequence switch spring 296, right-hand armature and back contact of relay 74 to ground. Sequence switch 106 is then moved out of position 15 and into its 110 normal position and sequence switch 114 is moved into its normal position in the same manner as above described.

While the sequence switch 106 is in position 115 12, a circuit is completed from grounded battery, winding of relay 122, upper left-hand and right-hand contacts of sequence switch spring 123, conductors 172 and 173, contacts 45 and 38, conductor 174, upper left-hand and lower right-hand contacts of 120 sequence switch spring 293, conductor 294, resistance 295, lower right-hand contact of sequence switch spring 111 to ground. Relay 122 energizes and by attracting its left-hand armature completes the above circuit for moving the sequence switch 32 out of position 3 and into position 4. When sequence switch 106 leaves position 12, relay 122 deenergizes and the sequence switch 32 is then moved out of position 4 and into 125 130

position 5 due to the above traced circuit through the left-hand armature and back contact of relay 122. Sequence switch 32 is then moved into its normal position, due 5 to a circuit being closed from grounded battery, power magnet of sequence switch 32, upper right-hand contact of sequence switch spring 33, conductor 336, normal segment 337, brush 209, conductor 196, lower left-hand contact of sequence switch spring 197 10 to ground. Magnet 66 deenergizes as soon as sequence switch 32 reaches position 11.

In case the calling subscriber abandons a call after the sequence switch 106 has 15 moved into position 5 in response to the second series of impulses and before the district selector sequence switch 32 has moved into position 4, the switches are released in substantially the same manner as just described. 20

If, however, the calling subscriber abandons the call after the second series of impulses and while the district sequence switch is in position 4, release takes place 25 as follows: As soon as the line circuit is opened by the receiver being replaced upon the switchhook, relays 80 and 98 become deenergized. The deenergization of relay 98 causes the sequence switch 103 to move from 30 position 2 to its normal position, and while moving through positions 3 to 10, the coin device associated with the calling line is operated in the manner described to refund the coin. The deenergization of relay 98 35 also opens the fundamental circuit, and therefore relay 122 deenergizes as soon as the brush 191 reaches an insulated segment of commutator 192. The deenergization of relay 122 stops the upward movement of 40 the brush shaft 190 and closes the above traced circuit for moving the sequence switch 32 out of position 4 and into position 5.

When the sequence switch 103 left position 45 12, relay 74 deenergized and closed a circuit for moving sequence switch 106 out of position 5 and into position 7. In position 7 of sequence switch 106, the above traced circuit for relay 340 is closed. Relay 340 becomes energized and causes the 50 restoration of sequence switches 106 and 114 in the manner above described. In position 7 of sequence switch 106, the fundamental circuit is closed for an instant from 55 grounded battery, winding of relay 122, upper contacts of sequence switch spring 123, conductors 172 and 173, contacts 45 and 38, contacts of sequence switch spring 123, conductors 172 and 173, contacts 45 and 38, 60 conductor 174, winding of polarized relay 175, armature and back contact of No. 0' counting relay, winding of stepping relay 176, upper contact of sequence switch spring 177, conductor 178, upper contact of sequence switch spring 126, conductor 125 to ground over the circuit previously described. Relay 122 becomes energized and closes the above traced circuit for moving sequence switch 32 out of position 5 and into position 6. Before sequence switch 32 70 will have had time to reach position 6, relay 340 (Fig. 3) will energize and sequence switch 114 will leave position 2. Therefore the circuit for relay 122 is opened at the upper contact of sequence switch spring 177. 75 Relay 122 deenergizes and closes a circuit for immediately moving sequence switch 32 out of position 6 and into position 7. Relay 212 becomes energized in position 7 of sequence switch 32 and closes the above 80 traced circuit for moving the sequence switch 32 out of position 7 and into position 8. It should be observed that since relay 122 deenergizes before sequence switch 32 reaches position 6, the circuit of updrive 85 magnet 188 is not closed to move the brush shaft 190 upward and therefore the selected set of brushes is not tripped into engagement with the contacts of the terminal banks. Therefore relay 212 will deenergize 90 as soon as sequence switch 32 reaches position 8 because the holding circuit therefore through the test brush 216 is open. The deenergization of relay 212 closes the above 95 traced circuit for moving the sequence switch 32 out of position 8 and into position 10. It will be observed from the above description that after the relay 74 deenergizes, the sequence switch 32 is moved from position 6 to position 10, a total of five 100 positions in practically one continuous movement. In the meantime sequence switch 114 has had to move from position 2 to position 18, a total of sixteen positions before the sequence switch 106 is moved 105 out of position 7. It is therefore evident that the sequence switch 32 reaches position 10 before the sequence switch 106 reaches position 12. As a result of this arrangement, when the sequence switch 106 does 110 reach position 12, a circuit is closed from grounded battery, left-hand winding of relay 212, lower left-hand contact of sequence switch spring 213, conductor 291, contacts 43 and 36, conductors 292 and 293, left-hand 115 armature and front contact of relay 340, lower contact of sequence switch spring 97 to ground. Relay 212 becomes energized and closes a circuit for moving the sequence switch 32 out of position 10 and into position 16. The district selector switch and sequence switch 32 are then returned to their 120 normal positions in the usual manner.

If the calling subscriber abandons the 125 call after the second series of impulses and while the sequence switch 32 is in position 6, the circuit of relay 122 is opened by the deenergization of relay 98, and therefore it deenergizes as soon thereafter as the brush 209 engages an insulated segment of the 130

commutator 210. The deenergization of relay 122 stops the brush shaft 190 with the tripped set of brushes in operative relation to a group of terminals, and also closes the above traced circuit for moving the sequence switch 32 out of position 6 and into position 7. The sequence switch 32 is moved out of position 7 and into position 8 by the energization of relay 212 and trunk hunting 10 then takes place in the usual manner. As soon as an idle trunk is found in the selected group the sequence switch 32 is moved into position 10. Sequence switch 32 is then returned to its normal position in the manner 15 last described, as the time required for the district selector switch to find an idle trunk, and the sequence switch 32 to move from position 6 to position 10, is less than the time required for the sequence switch 106 to 20 reach position 18.

The operation of the system is substantially the same as that described in case the calling subscriber abandons the call at any other time while the sequence switch is in 25 any position between positions 6 and 10. It will also be observed that since the circuit for moving the sequence switch 114 out of position 5 in the normal operation of the system is not closed at sequence switch 30 spring 365 (Fig. 3) until sequence switch 106 reaches position 7, the operation will substantially be the same as that just described in case the calling subscriber abandons the call at any time before sending out 35 the fourth series of impulses, and therefore the office selector switch will not be operated.

However, in the case where the calling subscriber abandons the call after sending 40 out four series of impulses and while the office selector is operating, release takes place as follows: As soon as the line circuit is opened by the receiver being placed upon the switchhook, relays 80 and 98 become de- 45 energized. The deenergization of relay 98 causes the sequence switch 103 to operate in the same manner as previously described to refund the coin to the calling subscriber. Sequence switch 32 is in position 10, se- 50 quence switch 106 is in position 7 and sequence switch 114 is in position 6 or 8 at this time. When sequence switch 103 leaves position 12, relay 74 deenergizes and closes the above traced energizing circuit for re- 55 lay 340. Relay 340 then becomes energized and causes the restoration of sequence switches 114 and 106 in the manner above described. When sequence switch 106 reaches position 12, the above traced circuit 60 for relay 212 is completed at the lower contact of sequence switch spring 97. Relay 212 becomes energized and causes the restoration of the district selector switch and the sequence switch 32 in the manner de- 65 scribed. As soon as brushes 216, 236 and

231 leave the terminals of the trunk leading to the office selector switch, the office selector switch is returned to its normal position in the well-known manner.

After the office selector switch has been 70 operated to find an idle trunk extending to an incoming selector switch, brush selection at the incoming selector switch does not take place until sequence switch 114 reaches position 10. But as previously described, 75 sequence switch 114 is not moved into position 10 in the normal operation of the system until the calling subscriber has dialed the completed number, at which time the sequence switch 106 is in position 10 and the 80 circuit for moving sequence switch 114 into 10 is closed at the lower right-hand contact of sequence switch spring 245. Therefore, if the calling subscriber abandons a call at any time after the office selector switch has 85 started operating and before dialing the complete number, release takes place in substantially the same manner as just described.

It will now be assumed that the calling subscriber abandons the call after dialing 90 the complete number and while either the incoming or final selector switches are operating, since the sequence switch 114 will be in a position beyond position 9. Under this assumption, the circuit for relay 340 is 95 not completed, and the connection is therefore made to the called line in the ordinary way, but before ringing current is applied to the called line, the connection is released in the following manner: As soon as the 100 called subscriber restores his receiver upon the switchhook, relays 80 and 98 deenergize. The deenergization of relay 98 restores, the sequence switch 103, whereupon the coin will be refunded to the calling subscriber in the manner described. When the sequence switch 103 leaves position 12, the circuit of cutoff relay 11 is opened, whereupon the line switch associated with the calling line is returned to normal. Relay 110 74 also deenergizes when the sequence switch 103 leaves position 12, but since sequence switch 106 is in position 10, its deenergization performs no function at this time. As soon as sequence switch 114 115 reaches position 18, the above traced circuit for sequence switch 106 is closed to move it into position 12. Sequence switches 106 and 114 are then restored to their normal positions in the manner described. Sequence switch 32 is moved out of position 10 and into position 12 as soon as the sequence switch 106 leaves position 12, as in the case of an ordinary call. Relay 29, however, will not be energized when the sequence switch 32 leaves position 11, since the calling line is at this time disconnected from the terminals 28, 89 and 90. The sequence switch 32 will therefore be moved into its normal position in the manner de- 120 125 130

scribed. Magnet 239 will not be energized to connect an idle coin and metering device since this circuit is opened at the right-hand armature and front contact of relay 29. From the above description, it will be seen that if the calling subscriber abandons a call at any time before talking connection has been established to a called party, the coin at the calling substation is refunded by the apparatus shown in the upper left-hand corner of Fig. 3 instead of a common coin and metering device shown in Fig. 2.

We will now assume that the calling subscriber desires a connection with a special operator. In the present disclosure this connection may be established by dialing the letter A twice. Upon the removal of the receiver by the calling subscriber an idle sender is connected to the calling line in the usual manner. In response to the first series of impulses, register 137 is moved into position 0. In response to the second series of impulses, register 163 is moved into position 0. After the second series of impulses, relay 119 (Fig. 4) is energized and moves the sequence switch 106 into position 5 in the usual manner. At the same time a circuit is completed from grounded battery, winding of relay 82, upper contacts of sequence switch spring 99, conductor 370, contact of register spring 371, contact of register 372, conductor 373, right-hand armature and front contact of relay 119 to ground. Relay 82 becomes energized and at its outer left-hand armature and front contact completes a locking circuit for itself. Relay 82 by attracting its inner left-hand armature opens the fundamental circuit and prevents the district selector from starting its brush selection. Relay 82 by attracting its right-hand armature completes a holding circuit for relay 80 from grounded battery, winding of relay 80, conductor 81, right-hand armature and front contact of relay 82, lower left-hand contact of sequence switch spring 111 to ground. Relay 82 also completes a circuit from grounded battery, power magnet of sequence switch 103, lower left-hand contact of sequence switch spring 104, outer left-hand armature and front contact of relay 82 to ground, for moving the sequence switch 103 out of position 2 and into position 12. While the sequence switch 103 is moved from position 3 to position 10, the coin is refunded to the calling subscriber in the manner described. As soon as the sequence switch 103 leaves position 11, relay 82 deenergizes and closes the fundamental circuit. Brush and group selection now takes place at the district selector in the usual manner. As soon as the district selector has finished its group selection, sequence switch 114 is moved into position 5 in the usual manner. The sequence switch

114 then moves out of position 5 and into position 9 due to the following circuit: grounded battery, power magnet of sequence switch 114, upper left-hand contact of sequence switch spring 199, conductor 379, contact of register spring 374 to ground. As soon as an idle trunk leading to a special operator is found, sequence switch 32 moves into position 10. A circuit is now completed from grounded battery, left-hand winding of relay 212, lower left-hand contact of sequence switch spring 213, conductor 291, contacts 43 and 36, conductors 292 and 362, contact of sequence switch spring 360, conductor 361, upper left-hand contact of sequence switch spring 117, conductor 101, right-hand armature and front contact of relay 74 to ground. Relay 212 energizes and at its inner armature and front contact, a circuit is closed for moving the sequence switch 32 out of position 10 and into position 12. As soon as the sequence switch 32 leaves position 11, the circuit of relay 74 is opened at the upper contact of sequence switch spring 30. Cut-off relay 11 is held energized, however, through the winding of relay 29 and lower right-hand contact of sequence switch spring 30. The deenergization of relay 74 causes the sequence switches 103, 106 and 114 to return to their normal positions in the manner described. In position 12 of the sequence switch 32, a circuit is closed from grounded battery, winding of relay 273, lower left-hand and upper right-hand contacts of sequence switch spring 179, left-hand armature and back contact of relay 368, brush 231, terminal 357, inner armature and back contact of relay 354, lamp 353 to ground. As soon as the operator plugs into the jack 355, the cutoff relay 354 is energized in the well-known manner. A circuit is then closed from grounded battery, resistance 356, outer armature and front contact of relay 354, terminal 359, brush 216, upper and lower left-hand contacts of sequence switch spring 182, winding of relays 368 and 31 in parallel to ground. Relay 31 becomes energized and completes a circuit from grounded battery, power magnet of sequence switch 32, lower left-hand contact of sequence switch spring 33, upper left-hand and lower right-hand contacts of sequence switch spring 310, righthand armature and front contact of relay 31 to ground, for moving the sequence switch out of position 12 into position 13. The calling line is now connected through to the operator's position over a circuit from the operator's telephone set (not shown) through the tip of jack 355, terminal 358, brushes 236, right-hand armature and front contact of relay 368, conductor 87, lower left-hand contact of sequence switch spring 88, terminal 89, brush 25, lower armature and front contact of relay 11, loop at substation 21, upper ar- 130

mature and front contact of relay 11, brush 26, terminal 90, lower right-hand contact of sequence switch spring 91, conductor 92, left-hand armature and front contact of relay 368, brush 231, terminal 357 to the operator's head set through the ring of jack 355. The connection is broken down by the operator moving the plug from the jack 355. Relay 354 becomes deenergized at that time 10 and opens the circuits of relays 31 and 368. The deenergization of relay 31 opens the circuit of relays 29 and 11 at its left-hand armature and front contact. These relays are so constructed as to deenergize before the 15 left-hand armature of relay 31 completes at its back contact another circuit for these relays. The deenergization of relay 11 releases the calling subscribers' individual line switch in the manner described. The de- 20 energization of relay 29 completes a circuit from grounded battery, power magnet of sequence switch 32, lower left-hand contact of sequence switch spring 33, right-hand armature and back contact of relay 29 to ground, 25 for moving the sequence switch 32 out of position 12 and into position 17. Since relay 29 is deenergized while the sequence switch 32 is moving from position 14 to position 18, magnet 239 is not energized and therefore an 30 idle common coin and metering device is not connected to the calling line. In position 18, the district selector and then sequence switch 32 are returned to their normal positions in the manner described.

35 What is claimed is:

1. In a telephone system, a plurality of subscribers' lines, connecting circuits and switches for establishing a talking connection from one of said lines to another, a coin 40 device associated with each of said lines respectively, controlling means for governing the operation of said coin devices, and means common to a group of connecting circuits for automatically associating said controlling means with any one of the group of connecting circuits used in establishing said connection in order to control the operation of the coin device of the calling line.

2. In a telephone system, a plurality of 50 subscribers' lines, connecting circuits and switches for establishing a talking connection from one of said lines to another, a coin device associated with each of said lines respectively, controlling means for governing the operation of said coin devices, and a 55 switch common to a group of connecting circuits for automatically associating said controlling means with any one of the group of connecting circuits used in establishing said connection in order to control the operation of the coin device of the calling line.

3. In an automatic telephone system, calling subscribers' lines, called subscribers' lines, connecting circuits and switches for 60 establishing a talking connection from a

calling line to a called line, a coin device associated with each of said calling lines respectively, a plurality of controlling devices, any one of which may be employed to variably control the operation of the coin 70 devices of said calling lines, and means for automatically associating an idle one of said controlling devices with a connecting circuit used in establishing a connection.

4. In an automatic telephone system, calling 75 subscribers' lines, called subscribers' lines, connecting circuits and switches for establishing a talking connection from a calling line to a called line, a coin device associated with each of said calling lines respectively, a plurality of controlling devices, any one of which may be employed to variably control the operation of the coin 80 devices of said calling lines, and a switch for automatically associating an idle one of 85 said controlling devices with a connecting circuit used in establishing a connection.

5. In an automatic telephone system, calling 90 subscribers' lines, called subscribers' lines, connecting circuits and switches for establishing a talking connection from a calling line to a called line, a coin device associated with each of said calling lines respectively, a plurality of controlling devices, any one of which may be employed to 95 variably control the operation of the coin devices of said calling lines, and means automatically responsive to the termination of a call by the calling subscriber for associating an idle one of said controlling devices with 100 a connecting circuit used in establishing a connection.

6. In a telephone exchange system, subscribers' lines, message registers and coin 105 devices associated with said lines, connecting circuits and automatic switches for extending a connection from one of said lines to another of said lines, controlling means for governing the operation of said registers and coin devices, and means common to 110 a group of said connecting circuits for automatically associating said controlling means with any one of the group of connecting circuits.

7. In a telephone exchange system, subscribers' lines, message registers and coin 115 devices associated with said lines, connecting circuits and automatic switches for extending a connection from one of said lines to another of said lines, controlling means 120 for governing the operation of said registers and coin devices, and a switch common to a group of said connecting circuits for automatically associating said governing means with any one of the group of connecting circuits used in establishing a connection.

8. In a telephone exchange system, telephone lines, message registers and coin devices associated with said lines, connecting 125

- circuits and automatic switches for extending a connection from one of said lines to another of said lines, a plurality of controlling devices any one of which being arranged to variably control the operation of the registers and coin devices associated with calling lines, and means for automatically associating an idle one of said controlling devices with a connecting circuit used in establishing a connection.
9. In a telephone exchange system, subscribers' lines, message registers and coin collecting devices associated with said lines, connecting circuits and automatic switches for extending a connection from one of said lines to another of said lines, a plurality of controlling devices, any one of which being arranged to variably control the operation of the registers and coin devices associated with calling lines, and a switch for automatically associating an idle one of said controlling devices with a connecting circuit used in establishing a connection.
10. In a telephone exchange system, subscribers' lines, message registers and coin collecting devices associated with said lines, connecting circuits and automatic switches for extending a connection from one of said lines to another of said lines, a plurality of controlling devices any one of which being arranged to variably control the operation of the registers and coin devices associated with calling lines, and means automatically operated in response to the termination of a call by a calling subscriber, for associating an idle one of said controlling devices with a connecting circuit used in establishing a connection therefrom.
11. In a telephone exchange system, a calling line, a called line, automatic switches for establishing a connection from said calling line to said called line, a toll device associated with said calling line, variably adjustable means for governing the operation of said switches, and means associated with said last mentioned means and controlled by the adjustment thereof for controlling the operation of said toll device.
12. In a telephone exchange system, a calling line, a called line, connecting circuits and automatic switches for establishing a connection from said calling line to said called line, a toll device associated with said calling line, a plurality of variably operable means for governing the operation of said switches, means for connecting an idle one of said governing means to a connecting circuit used in establishing said connection, and means associated with each of said governing means for variably controlling the operation of said toll device.
13. In a telephone exchange system, a calling line, a called line, connecting circuits and automatic switches for establishing a connection from said calling line to said
- called line, a toll device associated with said calling line, a sender for governing the operation of said switches, and controlling means individual to each sender for variably controlling the operation of said toll device.
14. In a telephone exchange system, a calling line, a called line, connecting circuits and automatic switches for establishing a connection from said calling line to said called line, a toll device associated with said calling line, a plurality of variably operable means for governing the operation of said switches, and controlling means individual to each variably operable means for variably controlling the operation of said toll device.
15. In a telephone system, a group of calling lines, other lines of different characters, connecting circuits and switches for establishing connections from said calling lines to said other lines, coin devices associated with said calling lines respectively, a controlling device for said coin devices common to said group of calling lines, means for connecting said controlling device to a calling line when a connection is completed therefrom to certain of said other lines, and means for preventing the connection of said controlling device to said calling line when a connection is completed therefrom to certain of said other lines.
16. In a telephone system, a group of calling lines, other lines of different characters, connecting circuits and switches for establishing connections from said calling lines to said other lines of different characters, coin devices associated with said calling lines respectively, a plurality of controlling devices any one of which may be used to control the operation of the coin device of any one of said calling lines, means for connecting an idle one of said controlling devices to a connecting circuit used in establishing a connection between a calling line and any one of certain of said lines of different characters, and means for preventing the connection of an idle one of said controlling devices to a connecting circuit when it is used to establish a connection between a calling line and any one of certain other of said lines of different character.
17. In a telephone system, a group of calling lines, other lines of different characters, connecting circuits and switches for establishing connections from said calling lines to said other lines, coin devices and message registers associated with said calling lines, a controlling device for said coin devices, and message registers common to said calling lines, means for connecting said controlling device to a calling line when a connection is completed therefrom to certain of said lines of different characters, and means for preventing the connection of

said controlling device to a calling line when a connection is completed therefrom to certain of said lines of different characters.

18. In a telephone system, a group of calling lines, other lines of different characters, connecting circuits and switches for establishing connections from said calling lines to said other lines, coin devices and message registers associated with said calling lines,
- 10 19. a plurality of controlling devices any one of which may be used to control the operation of any of the coin devices and the message registers associated with said calling lines, means for connecting an idle one
- 15 of said controlling devices to a connecting circuit used in establishing a connection between a calling line and any one of certain of said lines of different characters, and means for preventing the connection of an
- 20 idle one of said controlling devices to a connecting circuit when it is used to establish a connection between a calling line and any one of certain other of said lines of different characters.
- 25 19. In a telephone system, calling subscribers' lines, called lines connecting circuits and switches for establishing a talking connection from a calling line to a called line, coin devices and message registers associated with said calling lines, a controlling device for said coin devices and message registers common to said calling lines, means for connecting said controlling device to a connecting circuit, and means for causing
- 30 35 said controlling device to operate the coin device of the calling line to refund the coin to the calling subscriber when said connecting means is operated prior to the establishment of a talking connection to a called line
- 40 and to operate the coin device of the calling line to collect the coin and the message register thereof to charge the call when said connecting means is operated after a talking connection is established to a called line.
- 45 20. In a telephone system, calling subscribers' lines, called lines, connecting circuits and switches for establishing a talking connection from a calling line to a called line, coin devices and message registers associated with said calling lines, a controlling device for said coin devices and message registers common to said calling lines, means automatically operated in response to the termination of a call by a calling subscriber
- 50 for connecting said controlling device to a connecting circuit used in connecting said calling line to a called line, means arranged to cause said controlling device to operate the coin device of the calling line to refund
- 55 the coin to the calling subscriber when call is abandoned prior to the establishment of a talking connection to the called line, and means arranged to cause said controlling device to operate the coin device of the calling line to collect the coin and to operate the message register thereof to charge the call when said controlled device is connected to the controlling circuit after a talking connection has been completed.
- 60 21. In a telephone system, calling subscribers' lines, called lines, connecting circuits and switches for establishing a talking connection from a calling line to a called line, coin devices and message registers associated with said calling lines, a plurality of controlling devices for the coin devices and message registers common to said calling lines, means for connecting an idle one of said controlling devices to a connecting circuit used in establishing a connection between a calling line and a called line, and means for causing said controlling device to operate the coin device of the calling line to refund the coin to the calling subscriber when said connecting means is operated prior to the establishment of a talking connection to the called line and for causing said controlling device to operate the coin device of the calling line to collect the coin and to operate the message register thereof to charge the call when said connecting means is operated subsequent to the establishment of a talking connection to the called line.
- 65 22. In a telephone system, calling subscribers' lines, called lines, connecting circuits and switches for establishing a talking connection from a calling line to a called line, coin devices and message registers associated with said calling lines, a plurality of controlling devices for the coin devices and message registers common to said calling lines, means automatically operated in response to the termination of a call by a calling subscriber for connecting an idle one of said controlling devices to a connecting circuit used in establishing a connection between said calling line and a called line, means arranged to cause said idle controlling device to operate the coin device of the calling line to refund the coin to the calling subscriber when the call is abandoned prior to the establishment of a talking connection to the called line, and to cause said idle controlling device to operate the coin device of the calling line to collect the coin and to operate the message register thereof to charge the call when said controlled device is connected to the controlling circuit after a talking connection has been completed.
- 70 23. In a telephone system, a calling line, a coin device associated therewith, a called line, connecting circuits and automatic switches for establishing a talking connection between said lines, a plurality of controlling devices, each being arranged to control the coin device in a similar manner, means for associating one of said controlling devices with a connecting circuit during the establishment of said connection, and means for connecting a different controlling means to a connecting circuit sub-

75 80 85 90 95 100 105 110 115 120 125 130 message register thereat to charge the call when the call is completed.

70 75 80 85 90 95 100 105 110 115 120 125 130 21. In a telephone system, calling subscribers' lines, called lines, connecting circuits and switches for establishing a talking connection from a calling line to a called line, coin devices and message registers associated with said calling lines, a plurality of controlling devices for the coin devices and message registers common to said calling lines, means for connecting an idle one of said controlling devices to a connecting circuit used in establishing a connection between a calling line and a called line, and means for causing said controlling device to operate the coin device of the calling line to refund the coin to the calling subscriber when said connecting means is operated prior to the establishment of a talking connection to the called line and for causing said controlling device to operate the coin device of the calling line to collect the coin and to operate the message register thereof to charge the call when said connecting means is operated subsequent to the establishment of a talking connection to the called line.

22. In a telephone system, calling subscribers' lines, called lines, connecting circuits and switches for establishing a talking connection from a calling line to a called line, coin devices and message registers associated with said calling lines, a plurality of controlling devices for the coin devices and message registers common to said calling lines, means automatically operated in response to the termination of a call by a calling subscriber for connecting an idle one of said controlling devices to a connecting circuit used in establishing a connection between said calling line and a called line, means arranged to cause said idle controlling device to operate the coin device of the calling line to refund the coin to the calling subscriber when the call is abandoned prior to the establishment of a talking connection to the called line, and to cause said idle controlling device to operate the coin device of the calling line to collect the coin and to operate the message register thereof to charge the call when said controlled device is connected to the controlling circuit after a talking connection has been completed.

23. In a telephone system, a calling line, a coin device associated therewith, a called line, connecting circuits and automatic switches for establishing a talking connection between said lines, a plurality of controlling devices, each being arranged to control the coin device in a similar manner, means for associating one of said controlling devices with a connecting circuit during the establishment of said connection, and means for connecting a different controlling means to a connecting circuit sub-

sequent to the establishment of said connection.

24. In a telephone system, a calling line, a toll device associated therewith, a called line, connecting circuits and automatic switches for establishing a talking connection between said lines, variably operable means for governing the operation of said switches while establishing said connection, means associated with said last mentioned means for controlling said toll device prior to the establishment of said connection, and means for connecting a different controlling means to a connecting circuit subsequent to the establishment of said connection for controlling the operation of said toll device.
25. In a telephone system, a calling line, a toll device associated therewith, a called line, connecting circuits and automatic switches for establishing a talking connection between said lines, a plurality of variably operable means for governing the operation of said switches while establishing said connection, means for connecting one of said governing means to a connecting circuit used in establishing said connection, means individual to said governing means for controlling said toll device prior to the establishment of said connection, and means for connecting a different controlling means to said connecting circuit subsequent to the establishment of said connection to control the operation of said toll device.

26. In a telephone system, calling lines, called lines of different characters, toll devices associated with said calling lines, connecting circuits and automatic switches for establishing a talking connection between said lines, a plurality of controlling devices for governing the operations of said toll devices, means for connecting one of said controlling means to a connecting circuit during the establishing of a talking connection to control the toll devices of the calling line when a call is extended to a line of one character, and means for connecting another of said controlling means to a connecting circuit subsequent to the establishment of a talking connection to control said toll device of the calling line when a call is extended to a line of a different character.

27. In a telephone system, calling lines, called lines of different characters, a coin device connected to each of said calling lines respectively, connecting circuits and automatic switches for establishing a talking connection between said lines, a plurality of groups of controlling devices for governing the operations of said coin device, means for connecting a controlling means of one group to a connecting circuit prior to the establishment of a talking connection to a called line of one character to control the coin device of the calling line, and means for connecting a controlling means of another group to a con-

nnecting circuit prior to the establishment of a talking connection to a called line of a different character to control said coin device.

28. In a telephone system, calling lines, called lines of different characters, a coin device connected to each of said calling lines respectively, connecting circuits and automatic switches for establishing a talking connection between said lines, a plurality of controlling devices for governing the operations of said coin devices, means for connecting one of said controlling means to a connecting circuit during the establishing of a talking connection to a called line of one character to operate the coin device at the calling substation to refund the coin, means for connecting a different one of said controlling means to a connecting circuit, means for causing said last mentioned controlling means to operate the coin device at the calling substation to refund the coin when said last mentioned connecting means is operated prior to the establishment of a talking connection to a called line of a different character, and to operate the coin device at the calling substation to collect the coin when said last mentioned connecting means is operated subsequent to the establishment of a talking connection to a called line of the last mentioned character.

29. In a telephone system, a group of calling lines, each of said lines having a coin device associated therewith, another group of calling lines not equipped with coin devices, called lines, automatic switches for establishing a connection between any one of said calling lines and any one of said called lines, and means for earlier disconnecting from a connection a calling line which is not equipped with a coin device than one which is equipped with a coin device.

30. In a telephone system, a group of calling lines of one character, a group of calling lines of another character, a plurality of called lines, automatic switches for establishing a connection between any one of said calling lines and any one of said called lines, and means for earlier disconnecting a calling line of the first mentioned character from a connection than one of the second mentioned character.

31. In a telephone system, a group of calling lines, each of said lines having a toll device associated therewith, another group of calling lines not equipped with toll devices, called lines, automatic switches for establishing a connection between any one of said calling lines and any one of said called lines, a controlling device for said coin devices common to said calling lines and arranged to be connected with any one of them, and means under the control of a controlling device for releasing said switches and for allowing a calling line to be earlier disconnected from said switches when it is

not equipped with a toll device than when it is equipped with a toll device.

32. In a telephone system, a group of calling lines, each of said lines having a toll device associated therewith, another group of calling lines not equipped with toll devices, called lines, automatic switches including a switch individual to each calling line for establishing a connection between a calling line and any one of said called lines, and

means for releasing said automatic switches, said means being arranged to cause the individual switch of the calling line to be earlier released when the calling line is not equipped with a toll device than when it is 15 equipped with a toll device.

In witness whereof we hereunto subscribe our names this 3rd day of April, A. D. 1918.

ALBEN E. LUNDELL.
GEORGE THOMPSON.
